UNITED STATES PATENT OFFICE.

LOUIS WILLETT, OF ANNAPOLIS JUNCTION, MARYLAND.

HORSESHOE.

1,272,591.

Specification of Letters Patent. Patented July 16, 1918.

Application filed March 18, 1918. Serial No. 223,176.

To all whom it may concern:

Be it known that I, LOUIS WILLETT, a subject of the King of England, residing at Annapolis Junction, in the county of Howard and State of Maryland, have invented a new and useful Horseshoe, of which the following is a specification.

The device forming the subject-matter of this application is a supplemental horseshoe, 10 adapted to be connected with a horseshoe of ordinary construction to provide an anti-slipping means, when desired, the construction being such that the auxiliary shoe can be removed at any time readily and quickly.

15 The invention aims to improve the means whereby the auxiliary shoe is held on the main shoe, and to improve generally and to enhance the utility of devices of that type to which the present invention appertains.

20 With the foregoing and other objects in view which will appear as the description proceeds, the invention resides in the combination and arrangement of parts and in the details of construction hereinafter described and claimed, it being understood that changes in the precise embodiment of the invention can be made within the scope of what is claimed without departing from the spirit of the invention.

30 In the accompanying drawings;—

Figure 1 shows in bottom plan a horseshoe whereunto the device forming the subject-matter of this application has been applied;

35 Fig. 2 is a section on the line 2—2 of Fig. 1;

Fig. 3 is a section on the line 3—3 of Fig. 1; and

40 Fig. 4 is a section on the line 4—4 of Fig. 2.

The device forming the subject-matter of this application preferably is made of metal throughout and includes a main member denoted generally by the numeral 1, the 45 main member comprising a toe 2 having up-standing terminal projections 3, a heel 4 and a bar 5 connecting the heel and the toe. There is an opening 6 through the bar 5 communicating with a slot 7 in the forward 50 end of the bar above the toe 2. A locking member in the form of a lever 8 is disposed in the opening 6 of the bar 5 and is mounted to swing, in a direction at right angles to the plane defined by the main member 1, on 55 a pivot element 9 carried by the bar 5 and extended across the opening 6, the forward

end of the lever 8 being adapted to be received in the slot 7. In the rear end of the toe 2 there is a forwardly extended recess 10 communicating with a depressed seat 11, 60 the recess and the seat forming a shoulder 12 having an inclined upper face 14.

The heel 4 has a longitudinal opening 15 communicating with a transverse guide slot 16. A pivot pin extends vertically across 65 the opening 15 and is mounted at its ends in the top and bottom portions of the heel 4, the pivot pin being denoted by the numeral 17. In the top of the heel 4, transverse slots 18 are fashioned.

70 The numeral 19 denotes, generally, an operating lever having a head 20 and a handle 21. The head 20 of the operating lever is located in the opening 15 of the heel 4 and is mounted to swing on the pivot pin 17, 75 the head having arcuate slots 22. Grip bars 23 are mounted to slide in the guide slot 16 and are provided at their outer ends with overhanging fingers 24. In the inner ends of the grip bars 23 there are fashioned slots 80 25 which receive the edges of the head 20 of the operating lever 19. In the extreme inner ends of the grip bars 23, notches 26 are formed, the same being adapted to receive the pivot pin 17 when the grip bars 85 23 are moved inwardly as far as they will go. Pins 27 are mounted in the grip bars 23 and extend across the slots 25 of the grip bars, the pins passing through the arcuate slots 22 in the head 20 of the operating lever 19 and being received slidably in the slots 18 which are formed in the top of the heel 4. The grip bars 23 and the toe 2 are provided with calks 29 which may be of any desired construction, the calks prefer- 90 ably being removable and renewable.

95 The numeral 28 marks a horseshoe with which the structure forming the subject-matter of this application is adapted to be assembled. In operation, the shoe 28 is 100 placed on top of the toe 2 and on top of the grip bars 23, the part 4 lying between the heels of the shoe 28 and the projections 3 on the part 2 engaging the outer edge of the toe of the shoe 28. The rear end of the 105 lever 8 is swung upwardly, the forward end of the lever moving downwardly and engaging the toe portion of the shoe 28. The operating lever 19 is swung on the pivot pin 17, the arcuate slots 22 in the head 20 of the 110 operating lever coacting with the pins 27 to move the grip bars 23 inwardly until the

fingers 24 engage the shoe 28 at the outer edges of the heels thereof. When the operating lever 19 is swung on the pivot pin 17, the handle 21 of the operating lever, which is 5 resilient, enters the recess 10 and rides up along the inclined face 14, the forward end of the handle snapping down into the seat 11 behind the shoulder 12, the operating lever thus being held securely against accidental 10 detachment, but releasably at the will of an operator. It is to be observed that when the handle 21 of the operating lever 19 is received in the seat 11, the operating lever lies directly beneath the lever 8. The rear end 15 of the lever 8, therefore, cannot move downwardly, and the forward end of the lever 8 cannot move upwardly out of engagement with the toe portion of the shoe 28. In view of the foregoing, it will be obvious that the 20 operating lever 19 and particularly its head 20, forms a locking means which holds the lever 8 in position.

Having thus described the invention, what is claimed is:—

- 25 1. In a supplemental horseshoe, a main member; a retaining lever fulcrumed intermediate its ends on the main member to swing in a plane at right angles to the plane defined by the main member; and a laterally operating retaining means including an operating lever movable in a plane parallel to the plane defined by the main member, to actuate the laterally operating retaining

means, and to assume a position beneath the retaining lever, thereby to prevent the latter 35 from tilting.

2. In a supplemental horseshoe, a main member; a retaining lever fulcrumed intermediate its ends on the main member to swing in a plane at right angles to the plane 40 defined by the main member, the forward end of the retaining lever being adapted to coact with a main horseshoe to hold the supplemental horseshoe thereon; and movable means carried by the main member and engaging the rear end of the retaining lever to hold the latter against tilting movement.

3. In a supplemental horseshoe, a main member including a heel, a toe, and a connection between the heel and the toe; grip 50 bars mounted to slide transversely of the main member in the heel and having projections; and a lever mounted to swing in the heel, the lever having cam parts coacting with the projections to advance and retract 55 the grip bars, the toe having a part where-with the lever interlocks to hold the lever against swinging movement.

In testimony that I claim the foregoing as my own, I have hereto affixed my signature 60 in the presence of two witnesses.

LOUIS WILLETT.
